UNITED STATES PATENT OFFICE.

LOUIS V. ARONSON, OF NEWARK, NEW JERSEY.

DOLL.

1,140,651.

Specification of Letters Patent. Patented May 25, 1915.

Application filed February 27, 1915. Serial No. 10,914.

To all whom it may concern:

Be it known that I, LOUIS V. ARONSON, a citizen of the United States, and a resident of Newark, in the county of Essex and State of New Jersey, have invented certain new and useful Improvements in Dolls, of which the following is a specification.

The invention relates to improvements in toys as dolls, more particularly to such as are provided with talking or sound emitting mechanism.

It has for its object to enable some part or parts of the doll proper to move when the sound emitting mechanism is actuated and to construct the doll in such a manner that, if desired, said movement will not interfere with the normal movement or the position of said parts.

In the accompanying drawing which illustrates the invention, Figure 1 is a front elevation and Fig. 2 a side elevation of the improved doll. Fig. 3 is a detail view illustrating the attachment of the arm members.

Similar characters of reference designate corresponding parts throughout the several views.

Referring to the drawings, 11 designates the body portion proper which is constructed in any suitable manner and is herein shown as a hollow semi-cylindrical body open at the front. To the inner walls of said body is fixedly attached one member 12 of the sound emitting mechanism, the same being shown by way of example as a spring distended bellows and whose movable member 13 extends from said body portion and preferably outwardly from the front thereof. In pressing upon said movable member a suitable sound will be emitted by a whistle 14 or other sound producing device which may be attached, for example, to the member 12 as shown.

To the lower part of the body 11 may be pivotally attached the legs 15 by means of suitable resilient washers 16 and pin 16', as is well understood. The arms 17, however, are not as heretofore attached directly to the body but are pivotally attached by resilient washers 18 and pin 19 to ears 20 at opposite ends of a plate 21 which is fixedly secured to the outer and movable member 13 of the bellows. The arms 17, therefore, may effect a movement independent of the member 13 to which they are frictionally held by the said washers with sufficient strength to maintain any position in which they are

placed and will, furthermore, partake of any movement of the member 13 when the same is actuated. To plate 21 is fixedly secured, moreover, a plate 22 which carries the head of the doll, and the latter will thus be caused to follow the movements of the bellows member 13, the extent of movement of both head and arms being indicated by the position shown in dotted lines. The doll is thus provided with movable arms and legs, the former as well as the head of the doll being further movable when the doll is caused to emit a sound by pressing upon the bellows or the like.

I claim:

1. A figure toy, comprising a body and one or more movable parts attached thereto, sound emitting mechanism mounted on said body and having a portion adapted to be moved to cause said mechanism to respond, said movable part or parts being connected to said movable portion of the sound emitting mechanism, and means for holding said movable part or parts in different adjustments.

2. A figure toy, comprising a body and one or more movable parts attached thereto, sound emitting mechanism mounted on said body and having a portion adapted to be moved to cause said mechanism to respond, said movable part or parts being connected to said movable portion of the sound emitting mechanism, and resilient washers between said movable part or parts and the said body.

3. A doll, comprising a body portion, sound emitting mechanism mounted thereon and having a portion adapted to be moved to cause said mechanism to respond, and arms pivotally attached to said movable member.

4. A doll, comprising a body portion, sound emitting mechanism mounted thereon and having a portion adapted to be moved to cause said mechanism to respond, a head attached to said movable member, and arms pivotally attached to said movable member.

5. A doll, comprising a body portion, and a bellows and sound emitting device attached thereto, legs pivotally attached to said body portion, a head fixedly attached to the movable member of said bellows, and arms pivotally attached to said member.

6. A doll, comprising a body portion, and a bellows and sound emitting device attached thereto, a plate secured to the movable mem-

ber of said bellows and provided with ears at the sides, and arms pivotally attached to said ears.

7. A doll, comprising a body portion, and 5 a bellows and sound emitting device attached thereto, legs pivotally attached to said body portion, a plate secured to the movable member of said bellows and provided with ears at the sides, arms pivotally attached to said

ears, and a head fixedly secured to said 10 plate.

Signed at Newark, in the county of Essex, and State of New Jersey, this 26th day of February, A. D. 1915.

LOUIS V. ARONSON.
